UNITED STATES PATENT AND TRADEMARK OFFICE
CERTIFICATE OF CORRECTION

PATENT NO. : Des. 578,968 S
APPLICATION NO. : 29/285469
DATED : October 21, 2008
INVENTOR(S) : Robert F. Karliceck, Jr. et al.

Page 1 of 1

It is certified that error appears in the above-identified patent and that said Letters Patent is hereby corrected as shown below:

On the Title Page of the Patent

Section (54), "LED DEVICE" should be "LED ASSEMBLY"

Section (57) CLAIM, "The ornamental design for a LED device" should be
"The ornamental design for a LED assembly"

Section DESCRIPTION, "FIG. 1 is a side, top, perspective view of an LED device" should be "FIG. 1 is a side, top, perspective view of an LED assembly"

Signed and Sealed this

Twenty-seventh Day of January, 2009

JOHN DOLL
Acting Director of the United States Patent and Trademark Office
